(57) **CLAIM**

The ornamental design for a display package for a liquid absorbent wristband as shown and described.

DESCRIPTION

FIG. 1 is a perspective view of a first embodiment of a display package for a liquid absorbent wristband showing our new design, in a state of use;

FIG. 2 is a front perspective view thereof;

FIG. 3 is a back perspective view thereof;

FIG. 4 is a front elevation view thereof;

FIG. 5 is a back elevation view thereof;

FIG. 6 is a perspective view of a second embodiment of a display package for a liquid absorbent wristband showing our new design, in a state of use;

FIG. 7 is a front perspective view thereof;

FIG. 8 is a back perspective view thereof;

FIG. 9 is a front elevation view thereof; and,

FIG. 10 is a back elevation view thereof.

The broken lines in the forms of a wristband and a peg hook in FIGS. 1 and 6 depict environmental subject matter and form no part of the claimed design. The remaining broken lines in the drawings depict portions of the display package for a liquid absorbent wristband that form no part of the claimed design.
